UNITED STATES PATENT OFFICE.

HARRY M. WILLIAMS, OF LITTLE ROCK, ARKANSAS, AND JOHN W. DEAN, DECEASED,
LATE OF LITTLE ROCK, ARKANSAS, BY RUTH L. DEAN, ADMINISTRATRIX.

SUPERHEAT LOCOMOTIVE.

Application filed May 26, 1919. Serial No. 299,981.

To all whom it may concern:

Be it known that HARRY M. WILLIAMS, a citizen of the United States, residing at Little Rock, county of Pulaski, and State 5 of Arkansas, and JOHN W. DEAN, deceased, late a citizen of the United States, and a resident of Little Rock, county of Pulaski, and State of Arkansas, have invented certain new and useful Improvements 10 in Superheat Locomotives, of which the following is a specification.

Our invention relates to locomotives and particularly to superheat locomotives. More especially our invention relates to a superheat locomotive particularly adapted for 15 use in conjunction with a weed and grass burner such as forms the subject matter of our Patent No. 1,238,861, granted September 4, 1917, and of a co-pending application 20 Serial No. 307,471.

The object of our invention is to provide a locomotive for the purpose above mentioned of such construction that the quantity of superheated steam supplied to the 25 engine cylinders and to the burner may be regulated as found desirable in use so that the speed of the locomotive may be governed without increasing or diminishing the necessary supply of steam to the burner 30 or burners. Other objects will appear hereinafter.

With these objects in view our invention consists generally in a locomotive equipped 35 with a superheater supplied in the usual manner from the steam dome, the usual main throttle controlling the supply of steam to the superheater, auxiliary throttles controlling the supply of superheated steam to the engine cylinders, and a supply 40 pipe for the burners. Our invention further consists in means whereby the steam may be shut off from the steam chests of the cylinders through the main supply pipes and valves and supplied through a restricted 45 valved by-pass when the burner is in operation. Our invention further consists in a device as above mentioned further characterized by a valve in the supply pipe to the burners. Our invention further 50 consists in various details of construction and arrangements of parts as will be fully described hereinafter and particularly pointed out in the claim.

Our invention will be more readily understood 55 stood by reference to the accompanying

drawings forming a part of this specification, and in which

Figure 1 is a longitudinal section of the forward portion of a locomotive embodying our invention, portions being illustrated 60 in elevation.

Figure 2 is a transverse vertical section on the line 2—2 of Figure 1.

Figure 3 is a front elevation of a locomotive embodying a slightly modified form 65 of the invention, illustrated upon an enlarged scale, and

Figure 4 is a side elevation of the same upon a reduced scale.

Referring now to the drawings, 3 indicates the boiler of a locomotive having the usual fire tubes 4 and steam dome 5. Forward of the boiler is the usual smoke box 6 equipped with a smoke stack 7.

Arranged in the smoke box 6 is a superheater comprising a header 8 divided as at 9 into a chamber 10 for the saturate steam and a chamber 11 for the superheated steam. Suitable pipes 12 extend from the chamber 10 to the chamber 11 and for a greater portion of their length are arranged within the fire tubes 4 as indicated. The usual steam pipe 13 supplies steam to the superheater from the dome 5 and is equipped with the ordinary throttle 14. It is to be 85 understood that our invention is not limited to the specific form of superheater shown, but that this feature may be varied as desired.

Extending from the superheater are the 90 steam pipes 15 leading to the steam chests 16 of the engine cylinders. Interposed in each of the pipes 15 is an auxiliary throttle 17, controlled through suitable mechanism 95 18 from the engine cab.

A steam pipe 19 is provided for conducting superheated steam to a coupling or connection 20 for a flexible pipe or hose 21 adapted to extend to the grass burners. This may extend from the chamber 11 of the superheater header, as shown in Figures 1 and 2 of the drawings, or may extend from one of the pipes 15, as shown in Figures 3 and 4. Interposed in the pipe 19 is a suitable valve 22, preferably a globe valve 105 as illustrated. When the burner is in operation, it is desirable that the locomotive shall pass slowly over the track to accomplish the desired destruction of weeds and grass, or the melting of ice and snow. At 110

such time the superheated steam is supplied to the cylinders through a by-pass 24, supplied through a pipe 25 in communication with one of the pipes 15 above the respective valve 17. A valve 26 is interposed in the by-pass supply pipe 25, and this is controlled by mechanism 27 from the cab.

The burners forming the subject matter of the patent and application above specified are devices for projecting jets of heated fluid and vapor downwardly as the device passes along the track in order to burn or destroy the grass and weeds along the road-bed or for removing ice and snow from the tracks, switches, etc. It is obviously necessary that when superheated steam is employed as the burning medium, sufficient steam must be supplied to the burners to accomplish the desired result and that a greater supply than is necessary must be avoided to prevent waste. It is also obvious that the speed with which the device passes over the tracks must be under the control of the engineer without changing the volume of steam supplied to the burners. With the device above described the quantity of steam supplied to the burners may be regulated by means of the valve 22, the main throttle 14 being left open; and the speed of the device may then be regulated by the engineer by means of the valve 28 after having closed the auxiliary throttle 17.

The form of device shown in Figures 1 and 2 requires tapping the pipe 19 into the superheater header, but by using the form shown in Figures 3 and 4 no changes

are made within the locomotive. The supply pipe for the burners is attached to one of the pipes 15 and the by-pass supply pipe 25 is tapped to the other pipe 15; thus in a measure balancing the steam supply through the pipes 15.

We claim:

A locomotive including the boiler, smoke box and cylinder steam chests, in combination with a superheater, a steam supply pipe connecting said boiler and said superheater, a main throttle therein, steam pipes connecting said superheater and said steam chests, auxiliary throttles arranged in said pipes, a cross-connection communicating with each of said steam chests, a supply pipe for said cross-connection communicating with one of said superheat steam pipes above the throttle therein, a valve in the last said pipe, a steam pipe coupling for a burner, and a pipe for supplying superheated steam thereto, said pipe being connected to the opposite superheat steam pipe from that to which the cross-connection supply pipe is connected, and above the throttle therein substantially as described.

In testimony whereof we have signed our names to this specification in the presence of subscribing witnesses.

HARRY M. WILLIAMS.

RUTH L. DEAN,

Administratrix of John W. Dean, deceased.
